(57) **CLAIM**

The ornamental design for a portable power station, as shown and described.

DESCRIPTION

FIG. 1 is a top, front, left side perspective view of a portable power station, showing my new design;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof;
FIG. 7 is a bottom plan view thereof;
FIG. 8 is an enlarged left side detail view of the portable power station of FIG. 4;
FIG. 9 is an enlarged left side enlarged detail view thereof;
FIG. 10 is an enlarged top, front, left side detail view of the portable power station of FIG. 1; and,
FIG. 11 is an enlarged top, front, left side detail view thereof.
